BUMPER STICKER HOLDER

Melvin E. Clark, 3025 E. Bellevue,
Phoenix, Ariz. 85008

Filed Jan. 2, 1974, Ser. No. 430,188

Term of patent 14 years

Int. Cl. D8—08

U.S. Cl. D8—243

FIG. 1 is a front perspective view of a bumper sticker holder.

FIG. 2 is a rear perspective view.

FIG. 3 is a frontal view of my present invention.

FIG. 4 is a top view of my present invention, taken along lines 4—4 as shown in FIG. 3.

FIG. 5 is an end view of my present invention, taken along lines 5—5 as shown in FIG. 3.

I claim:

The ornamental design for a bumper sticker holder, as shown.
